UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

WEB MANIPULATING MECHANISM FOR PAPER FOLDING MACHINES

Application filed February 24, 1928, Serial No. 256,712. Renewed May 5, 1931.

The principal objects of this invention are to provide means for leading the web into the folding couple of a newspaper folding machine in such a way as to prevent choking in the folding mechanism, thus reducing delay and sometimes damage to the machine; to provide means whereby the web will be positively backed up when the collecting cylinder pins are forced into it so that the paper will not yield and also to provide a longer space on the web for receiving the pins so that they will not have to be operated at as high speed as has been necessary for the same speed of production, thus permitting of the making of the cams less steep than has been the case heretofore and increasing their life; to provide for holding the web in a taut condition against the surface of the cutting cylinder while being perforated by the pins so that the leading edge of a collected newspaper section will be held more firmly, thus reducing the strain on the paper while the pins are penetrating and also to provide for backing up the paper when it is perforated by the pins on the collecting cylinder; to provide a yielding member around which the paper passes in passing to the folding couple adapted to sufficiently ease the strain on the paper and on the pins without permitting them to lose their hold, thus keeping the paper under a firm but gentle tension at this point and to obviate the tearing out of the pin holes or the breaking of the pins; to provide means for increasing the longitudinal edge folded line of the product during its travel from the former to the folding cylinders without necessitating the slowing down of the nipping rolls to a speed as low as that of the web and preventing the blowing of the sheets apart during their rapid feeding to the folding couple and also preventing the buckling of the folding line which causes paper wrinkles and is apt to release the product from the pins, and to provide for increasing the speed at which large collected newspapers can be run.

Other objects and advantages of the invention will appear hereinafter.

Reference is to be had to the accompanying drawings in which

Fig. 1 is a side view of a cutting and col-

lecting cylinder arranged according to this invention;

Figs. 2 and 3 are end views of the same showing the parts in two different positions;

Fig. 4 is a transverse sectional view of the folding couple;

Fig. 5 is a view of the folded product before it enters the rolls;

Fig. 6 is a similar view showing the completed product;

Fig. 7 is a diagrammatic end view of the folding couple, and

Fig. 8 is a similar view showing one of the old methods.

This method is designed for use in connection with a folding machine well known in the newspaper producing art and in fact capable of use in connection with any printing machine in which a plurality of webs are fed to the folding couple and products having a large number of sheets are produced. It is shown as applied to a folder of an ordinary newspaper press in which the once folded sheet runs from the former to the cutting and folding cylinders, as indicated in Fig. 7. When it is desired to collect or superimpose one product upon another, the pins on the cutting cylinder are put into operation so that they pick up the first section or product that comes along and carry it around the cutting cylinder, as indicated in that figure, and superimpose on it the following section.

The sheets are then taken from the cutting cylinder by the pins of the folding cylinder and carried around the latter and folded in the usual way, one of these sections within the other. It is customary at the present time to produce newspapers containing as many as sixty-four pages. When such a paper is made by the collecting process, it contains two sections of thirty-two pages each. The leading edge of one of these sections, containing sixteen sheets, is apt to be blown open when it moves through the air so that when it arrives at the intersection of the two cylinders, where the pins of the collecting cylinder let go and the pins of the folding cylinder take hold, the leading edges on the collecting cylinder are apt to be apart.

This causes it to blow off the pins before they can be released and produces paper chokes and consequent delays.

The collecting cylinder pins have to be withdrawn almost instantaneously at the points of intersection as they must keep a firm hold on the sixteen-sheet section until the pins of the folding cylinder are thrust through it and must be withdrawn at once. Otherwise they would carry the innermost sheets of the collected section around the second time. When this happens it causes a choke in the folding mechanism with necessary delay and frequently results in damage to the machine.

It is customary to employ a very steep cam for operating these pins on account of the above reasons. The cam, being so steep, is battered to pieces in a short time when the machine runs at high speed and the tendency is to keep increasing the speed of these machines. One of the features of this invention is to increase the arc through which the pins can be introduced into, and withdrawn from, the paper section and thus reduce the abruptness of the cam for operating them to mitigate the difficulties above mentioned. I do this by wrapping the webs, as they approach the bite, about the cutting and collecting cylinder through a considerable arc, thus allowing the pins to enter the web at an earlier stage and to be withdrawn more slowly than has been the case heretofore. I also provide for holding the web down around the collecting cylinder and contacting with it at a point near where the pins penetrate.

Another feature is the backing up of the web where it is penetrated so that the pins will enter it more easily and the strain on the pins is reduced. Also the pins on the folding cylinder engage the web when it is backed up by the cutting and collecting cylinders, as will be seen by comparison of Figs. 7 and 8, so that in both cases the pins penetrate a web supported on the opposite side instead of being forced into the web which is supported only at two distant points.

Another feature of this invention is the introduction of a yielding guide at some point between the former and the rotary folding mechanism. The paper passes around this guide which is arranged to yield sufficiently to ease the strain on the paper and pins without causing the pins to lose their hold. The guide keeps the paper under a firm but gentle tension.

I also provide for creasing the longitudinal folded line of the product as it passes from the former to the folded cylinders. This prevents a bulky fold at this point which might allow the sheets to get apart on account of the air getting into it and also prevents buckling because of the sharp crease along the edge.

Referring to the accompanying drawings I have shown a folding couple consisting of the usual folding cylinder 10 and cutting and collecting cylinder 11. These have their respective pins 12 and 13 which work practically in the usual way, except that, as they do not have to be operated as fast as before, the cam operating them can be less abrupt and more durable.

In order to accomplish several of the objects above mentioned, I pivot on the folder frame, on studs 14, a frame 15. Only one of the two studs 14 is shown. This frame 15 carries a shaft 16 on which is a roll 17 extending across the machine. This roll has 80 recesses 17^a for receiving the pins 13. This frame 15 is normally forced downward by springs 18 against a stop 19 but is capable of yielding backwardly against a stop 20, these stops being adjustable. This roll is placed in such position that the web or section of paper coming down from the former folder 29 above will be directed out from a direct path therefrom to the folding couple, as shown in Fig. 7. It assumes a path of travel 90 in which it is considerably wrapped about the cutting and collecting cylinder 11, as shown in the other figures. This roller needs no other operation or attention, being forced yieldingly into place and capable of moving 95 backwardly against the springs whenever special resistance is encountered.

I have shown on the same frame 15, the means for forming the crease, although it could be placed at any other convenient position. This takes the form of a shaft 21 pinned to one frame 15 and carrying a pivoted arm 22 which carries a creasing roller 23 mounted on a stud carried by this pivoted arm 22. Around the shaft 21 is a coiled 105 spring 24 which is fixed at one end to a collar 25 that can be adjusted around the shaft and held in adjusted position by a screw 26. The spring is secured at the other end to the arm 22. This spring holds the creasing roller 110 down against the yielding roller 17. The shaft 16 is geared to the shaft of the cutting and collecting cylinder by gears 27 so that it is driven positively but the creasing roller is driven only by friction.

These parts are shown as used in connection with the ordinary knurled nipping rollers 28 receiving the folded web from the usual folder former 29. It will be understood of course that the section of the newspaper containing a large number of sheets is delivered below the former so it is folded longitudinally on itself at one edge.

The nipping rollers 28 are arranged ordinarily so as to run at a greater speed than the web, the effect being to keep the web taut and to do this whether the printing blankets on the printing press are new or worn down. They bear on the margins of the sheet only. On account of their running faster than the 130

sheet, it is not practical to set them hard against one another because they would then tear pieces out of the paper on account of their excess speed. They are merely close enough to exercise a drawing action but not tight enough to tear the paper. The fold, therefore, comes through in about the form indicated in Fig. 5. With a large product having perhaps sixteen sheets this loose fold is dangerous. When running at high speed the air is apt to get in and blow the sheets apart, causing a choke. Another danger is that the folded line is apt to buckle while being carried around the collecting cylinder. This prevents the product from lying smooth on the collecting cylinder and wrinkles the paper. The paper is held on the pins loosely which is apt to cause further trouble.

By placing a pair of creasing rolls between the nipping rollers and folding couple, the folded line of the whole product is ironed down to an even thickness as indicated in Fig. 6, thus eliminating the dangers above mentioned. It is for this purpose that the creasing roll 23 is used. The spring 24 is made strong enough to crease the fold of a large product but adapted to yield enough to adjust itself suitably to any change that may be made in the number of sheets run through the machine. Also its force can be adjusted by using the screw 26. This roll preferably is made smooth and can be run at web speed or a little faster if desired. It is convenient to run this creasing roller in cooperation with the yielding roller 17, as I have described, thus forming a creasing couple, but a separate creasing couple located elsewhere will perform this function in accordance with this invention. If either of these rollers 17 or 23 is roughened or knurled on the surface they will have to be run substantially at paper speed.

The yielding roller 17, as stated, is used to secure a wide arc of contact of the incoming paper on one of the cylinders of the folding couple, thus increasing the length of time during which the pin cams and the pins have to operate so that they can move more slowly. This permits the making of the pin cams less steep and more durable as above stated. The use of a roller at this point for producing this result is very convenient and permits of combining with the creaser roller 23 in a very simple manner.

It will be seen that the leading edge of the folded product as shown in Fig. 7, is held to the cylinder 11 by the wrap of the web part way around it and that the pins now begin to withdraw immediately, thus leaving the leading edge of the section bound to the cylinder by the layer of the incoming web wrapped over it. It is held in this way more firmly than by the pins in the old construction shown in Fig. 8. These two figures are presented to show how much more slowly the

pins can be withdrawn, as shown in Fig. 7, than as shown in Fig. 8.

Another advantage of this is that the leading edge is flattened and under firm control by the time it reaches the intersection of the cylinders where it must pass from the collecting cylinder 11 to the folding cylinder 10. I find that I am able to double the speed at which large collected newspapers may be run through the folder by this mechanism.

The way in which the web is backed up when the pins enter it from the cutting and collecting cylinder will be obvious from an inspection of Fig. 7 and it is to be observed that the pins 12 on the folding cylinder enter the web when it is firmly backed up by the cutting cylinder, as shown in Fig. 4. Heretofore the web has been entirely without backing at the point where the pins have entered, or as indicated in Fig. 8. The tearing of the web on this account is avoided by the present invention.

It will be seen that the creasing roller also constitutes a resilient guide. As the printing blankets on the presses are gradually beaten down by use, the effect is that the circumference of the cylinder gradually grows less and it feeds less and less paper to the folding cylinders. When the blankets are replaced with fresh ones more paper is suddenly fed to the folders. It has been necessary, therefore to give the folding and collecting cylinders a diameter larger than would be required mathematically so that their pins will have a firm hold on the product even when new blankets are put in. On this account the pins are apt to tear the paper or produce long slits in it when the product is fed by old blankets. The strain on the pins is great and they sometimes break. It is for this purpose that the roller 17 is made yielding so that it will give sufficiently to ease the strain on the paper and on the pins in accordance with the amount of paper being fed to it. In other words, this roller 17 acts as a tension guide and prevents the paper being put to a rigid strain, due to the change in size of the impression cylinder.

It will be understood, of course, that the roller or guide for producing this result can be made separate from the yielding roller 23 and placed elsewhere in the machine if desired.

Although I have illustrated and described only one form of the invention I am aware of the fact that modifications can be made therein by any person skilled in the art without departing from the scope of the invention as expressed in the claims. Therefore, I do not wish to be limited in these respects but what I do claim is:—

1. The combination with a folding couple and means for delivering the web thereto, of means for deflecting the web out of its normal straight path straight into the bite of

70

the folding couple and wrapping it part way around the collecting cylinder member of said couple before it passes into the bite.

2. The combination with a folding and collecting couple, of means for deflecting the web just before it passes into the space between the folding and collecting cylinders and wrapping it part way around the collecting cylinder to enable that part of the web to bear on the leading edge of the collected section to assist in holding the said leading edge while in the act of collecting.

3. The combination with a folding couple, of means for wrapping the incoming web around the leading edge of the first layer on the cutting and collecting cylinder throughout a material part of the circumference of the said cutting and collecting cylinder to help hold the leading edge in position when it comes to the space between the two cylinders of the couple.

4. The combination with a folding and collecting couple, of a yielding guide arranged to engage the web and deflect it laterally against the surface of the cutting and collecting cylinder, to wrap the incoming web around the said cutting and collecting cylinder throughout a part of its circumference.

5. The combination with a folding couple, comprising a folding cylinder and a cutting cylinder, of a roller supported above the cutting cylinder, but spaced therefrom for deflecting the web just before it passes into the space between the folding and cutting cylinders, and yielding means for forcing the roller toward the cutting cylinder.

6. The combination with a folding couple comprising a cutting cylinder, of a roller mounted in the normal path of the web thereto, means for yieldingly forcing it toward the web and means for rotating the roller positively with the cutting cylinder.

7. The combination with a folding couple, of a frame pivoted on the machine having a bearing, a roller carried in said bearing and extending from end to end of the folding couple, said roller being located in a position to deflect the web so it will wrap part way around one of the cylinders of said couple.

8. The combination with a folding couple, of a frame pivoted on the machine having a bearing, a roller carried in said bearing, said roller being located in a position to deflect the web so it will wrap part way around one of the cylinders of said couple, and yielding means for forcing said roller toward the adjacent cylinder.

9. The combination with a folding couple, comprising a folding cylinder and a cutting cylinder, of a roller supported above the cutting cylinder, but spaced therefrom for deflecting the web just before it passes into the space between the folding and cutting cylinders, yielding means for forcing the roller toward the cutting cylinder, and adjustable

stops for limiting the motion of the yielding roller toward and from the cutting cylinder.

10. The combination with a folding couple comprising a folding cylinder and a cutting and collecting cylinder and pins carried by the cutting and collecting cylinder, of means whereby the pins can start to penetrate the web at a point nearer the cutting and collecting cylinder than a line drawn tangent to the two cylinders at the point of contact. 75

11. The combination with a folding couple of empaling pins on the cutting cylinder, of a yielding guide in a position to engage the web as it passes thereto and deflect the web toward said empaling pins, whereby the guide is adapted to yield slightly when the pins penetrate the web and the strain on the paper will be eased at this time without permitting the pins to lose their hold. 80

12. The combination with a folding couple comprising a cutting and collecting cylinder and movable pins carried thereby for penetrating the web, of means for guiding the web in a path toward the point of contact of said cylinders, such that the pins will penetrate the collected section and second section of the web at a point near the top of the cutting and collecting cylinder. 85

13. The combination with a folding couple comprising a cutting and collecting cylinder and movable pins carried thereby for penetrating the web, of means for guiding the web over the surface of the cutting and collecting cylinder toward the point of contact of said cylinders to such an extent that the pins will penetrate the collected and second sections of the web while they are in contact with each other and throughout a considerable distance along the surface of the cutting and collecting cylinder, thereby permitting the pins to have a comparatively slow motion of insertion and withdrawal. 95

14. The combination with a folding couple comprising a cutting and collecting cylinder having pins for penetrating the web, of means so arranged as to cause the pins to enter an incoming web throughout a comparatively long distance along the circumference of the cylinder and thus have an opportunity to enter the web and leave it at a comparatively low rate of speed. 110

15. The combination with a folding couple having empaling pins, of a yielding guide for the web located in position to cause the web to wrap part way around the cutting and collecting cylinder before it engages the folding cylinder, said guide having spaces for receiving the empaling pins of the cutting and collecting cylinder and areas separating said spaces for backing up the web when the pins penetrate said spaces. 120

16. The combination with a folding couple comprising a folding cylinder, a cutting and collecting cylinder and impaling pins on the latter, of a guide in position to back up the 130

web positively when the impaling pins on the cutting and collecting cylinder penetrate it.

17. The combination with a folding couple comprising a folding cylinder and a cutting and collecting cylinder and pins carried by each cylinder for penetrating the web and feeding it forward, of means arranged between said cylinders for backing up the web when the pins on the cutting and collecting cylinder penetrate it.

18. The combination with a folding couple comprising a folding cylinder and a cutting and collecting cylinder, of means whereby the web is backed up firmly by the cutting and collecting cylinder throughout a material arc of its circumference when it comes to the position for receiving the pins of the folding cylinder.

19. The combination with a folding couple comprising a folding cylinder and a cutting and collecting cylinder, and reciprocable pins carried by said cylinders for penetrating the web and feeding it positively, of means for directing the web to the couple in such a path that the web will be backed up by the cutting and collecting cylinder when the pins of the folding cylinder penetrate it.

20. The combination with a folding couple and means for guiding a longitudinally folded web thereto, of a creasing couple located at one edge of the web for engaging the longitudinal fold at that edge and flattening it out before it reaches the folding couple.

21. The combination with a folding couple, of a guide roller located in a position to engage the web, and a creasing roller engaging the surface of the guide roller at its end only for creasing the longitudinal fold at that edge, with mechanical means for driving the guide roller, the creasing roller being driven by friction against the running web.

22. The combination with a folding couple, of a yielding roller located in a position to divert the web from a straight path and wrap it slightly around one of the members of the folding couple, a yieldingly mounted creasing roller engaging the surface of the yielding roller at the edge of the web for creasing the longitudinal fold, and means for positively driving the yielding roller at approximately web speed, said creasing roller being driven by friction against the running web.

23. The combination with a folding couple and a yieldingly mounted roller engaging the web and diverting it out of its normal path, of a frame on which one end of said yielding roller is movably mounted, a non-rotatable shaft on said frame, an arm pivoted on the shaft, a spring for normally moving the arm toward the roller, and a creasing roller mounted on the arm and free to turn on said shaft and normally pressing against the yielding roller.

24. The combination with a folding couple and a guide roller engaging the web, of a

frame on which said guide roller is movably mounted, a shaft on said frame, an arm pivoted on the shaft, a spring for normally swinging the arm toward the roller, and a creasing roller mounted on the arm and free to turn on said shaft and normally pressing against the yielding roller.

25. In a paper web folding device, the combination with a longitudinal folder, of a transverse folding mechanism, a web propelling device placed between the longitudinal folder and the transverse folding mechanism, means for wrapping the web around a part of one member of the transverse folding mechanism and applying a yielding tension to the web, and means positioned between the longitudinal folder and the transverse folder for creasing the folded line of the longitudinally folded web.

26. The combination with a folding couple comprising a folding cylinder and a collecting cylinder provided with impaling pins, the latter adapted to collect one product upon the other, with means other than the folding cylinder for reinforcing the web while the impaling pins of the collecting cylinder penetrate it.

27. The combination with a folding and collecting couple, of means for deflecting the web over against and part way about the collecting cylinder, the said deflecting means having clearances for the pins carried by the collecting cylinder so that the said pins shall have a free passage through the deflecting means.

28. The combination with a folding and collecting couple, of means for deflecting the web over against and part way about the collecting cylinder, the said deflecting means being so positioned as to afford clearance space for the pins between the deflecting means and the collecting cylinder.

In testimony whereof I have hereunto affixed my signature.

HENRY A. WISE WOOD.
